UNITED STATES PATENT OFFICE.

ROBERT A. BROOKS, OF CHICAGO, ILLINOIS.

FLUSHING APPARATUS.

Application filed January 8, 1920. Serial No. 350,200.

To all whom it may concern:

Be it known that I, ROBERT A. BROOKS, a citizen of the United States, residing at Chicago, in the county of Cook and State of Illinois, have invented certain new and useful Improvements in Flushing Apparatus, of which the following is a specification.

My invention relates to siphonic flushing devices adapted to be used to control the flush of water necessary to flush out closet bowls of any of the various types in common use in water closets, and is intended for the same general purposes as the siphonic flushing and metering devices shown in Patents Nos. 1,265,601 and 1,315,207 heretofore granted to me. The object of my present invention is the improvement and perfectioning of devices of this type, and the production of a flushing device which shall be efficient, durable, economical to manufacture and install, and shall possess various novel and desirable features of construction and arrangement which will be apparent from the description hereinafter given. In the appended claims I have more particularly pointed out the essential elements of my invention, it being understood, however, that various changes in the construction and arrangement of parts are possible without departing from the substance of my invention or the scope of such claims.

In the accompanying drawings forming part of this specification, Figure 1 is a front elevation of connected flushing devices embodying my invention as used in a system employing my invention and employing a master supply tank and a plurality of flushing devices for associated closet bowls; Fig. 2 is a top plan view of one of the devices; Fig. 3 is a vertical section of the device on the line 3—3 of Fig. 2, looking in the direction of the arrow; Fig. 3^a is a fragmentary section of the lower portion of the same, with the main piston and associated parts in the position occupied as the piston is descending; Fig. 4 is a vertical section on the line 4—4 of Fig. 2; Fig. 5 is a section in the same plane of a portion of the device, showing the timing piston in a different position; and Figs. 6 and 7 are detail views showing the relief valves which are used to respectively check and stop siphonic action.

The same reference characters indicate the same parts in all the figures of the drawing.

My novel flushing device is more partic-

ularly intended for installations in which a single master or supply tank, in which the water is maintained at a substantially constant level by a suitable admission valve, is connected by a line of piping of large capacity with devices individual to the closets of the system, in which devices the water normally stands at the level determined by the master tank. In Figure 1 of the drawings, the water in the supply tank A is maintained at a substantially constant level by the float-actuator inlet valve B, and in the line of supply piping C, which extends through all the closets, are interposed the flushing devices D, one at the back of each closet. The tank and flushing device are arranged at such level as to give a proper flush of water to the closet,—say about six feet from the floor.

The casing of my novel flushing device may consist of a single hollow casing 1, the front part 2 of which is open at the top, the lower portion of this open-topped part constituting a piston chamber 3. Communicating at the bottom with the piston chamber is a vertical smaller rear chamber 4, which constitutes the ascending leg of the siphonic passage. The descending leg is formed by a pipe 5, brazed to a nut 6 which is screw-threaded to engage a central threaded seat formed in the lower wall of the casting centrally of the chamber 4, and the discharge pipe 7 secured to the nut 6 in suitable manner, as by the union 8, leading to the closet bowl. The top of the chamber 4 is closed by a cover casting 9, bolted to the casing 1, this cover casting in the present instance being formed with a bracket lug 10 through which the device may be secured to the adjacent wall of the closet.

To provide for connecting the device in the line of supply piping C, the casing 1 is formed with opposite bosses 11 formed around opening 12 in the casing wall above the level of the piston chamber 3. These bosses are tapped to receive bolts 12^a by means of which orificed clamping rings 13 may be drawn up forcibly toward the bosses, and the registering openings in each boss and associated cap are oppositely chambered to form a wedge-shaped recess to receive a ring of suitable compressible packing material 14, as lead or other soft metal, surrounding the section of piping which extends into them. In this manner a firm joint is secured without the necessity of cutting the

piping with the accuracy which would otherwise be necessary, and forming threads thereon.

Within the piston chamber or forcing chamber 3 is arranged a pumping piston, comprising in the present instance a perforated disk 15 to which is secured a downwardly extending headed stud 16, upon which latter is slidably mounted a circular 10 check plate or valve 17. In the normal lowermost position occupied by the parts when at rest between flushing operations the head of the stud rests upon the bottom wall of the piston chamber, and the check plate 15 rests upon the upper face of such head, permitting free communication between the chambers 3 and 4. The piston is lifted through a rod 18 pivotally connected with an actuating lever 19 which is fixed to a 20 short rock-shaft 19^a journaled in a pair of ears formed on a pivot block 20 bolted to a lug 21 extending laterally from the top of the casing wall, and which is actuated by means of a rod 22 connected to its outer end. 25 This rod may be operated either manually, or automatically through suitable connections with the closet in a manner which is well known in the art and which therefore need not be here illustrated or described. In 30 the present instance a weight 23 is hung to the inner end of the lever 19 to assist the return of the piston to its normal lowermost position after having been actuated, although the weight and proportions of the 35 parts may be made such that this weight may be dispensed with.

When the parts of the device are at rest in normal position occupied during the intervals between flushing operations, the space 40 at the top of the siphonic passage in the chamber 4 is in communication with the atmosphere through two valves, both of which are automatically closed by the operation of the actuating lever to initiate a flushing operation. These valves, through connection 45 with a timing mechanism, are successively opened after the primary flushing flow has occurred to first cause a diminished flow of water and thus cause a refill of the closet 50 bowl, and then entirely break the siphon and stop the refill flow. For the purpose of diminishing the flow I provide a small tube 24 brazed or otherwise secured to the cover casting 9 forming the top wall of the chamber 4 and extending downwardly a short 55 distance within the pipe 5 which forms the upper portion of the descending leg of the siphon. The upper end of this tube 24 is formed as a valve seat with which is arranged to cooperate a valve 25. To entirely 60 interrupt all siphonic action I provide a valve 26 arranged to cooperate with a valve seat 27 opening directly into the chamber 4. The valves 25 and 26 are opened in the order 65 named, (after having been closed in a man-

ner hereinafter described) by means of a lever 28 pivoted between opposite posts 29 rising from the cover casting 9 and arranged to engage nuts 25^a and 26^a carried respectively by the upwardly extending stems 25^b 70 and 26^b of such valves.

The timing mechanism which is arranged to cooperate with the valves 25 and 26 includes a liquid-filled cylinder 30, which cylinder, in the present instance, consists of a cylindrical sheet metal cup brazed to a cap piece formed with a vertical lug 31 by means of which it is secured to the casing 1, and with a neck 32 which rises to the level of such casing. Within the cylinder 30 is arranged a reciprocating retarding piston 33 loosely confined between a curved arm 34 and a block 35 fixed to the lower end of the stem 36 of the piston mechanism. The stem 36 extends upwardly through an orificed plug 37 which closes the top of the neck 32 of the cylinder and at its top is equipped with a contact member 38 arranged to cooperate with the lever 28 before mentioned. The curved arm 34 holds the piston 33 in tilted position when the piston is at rest in lowermost position and while being lifted, and the orifice around the stem is larger than such stem with the result that liquid above the piston may pass through this orifice and around the edge of the piston readily when the latter is lifted. When descending, the piston assumes a horizontal position, as shown in Fig. 5, bringing up against the block 35 and closing the central opening and the liquid can only escape slowly through the restricted marginal opening around the periphery of the piston, thus retarding the return stroke of the piston.

It may be stated that while water or almost any other liquid of proper fluidity may be used in the timing cylinder, I preferably employ a fluid such as kerosene which is non-freezing and non-volatile in order that the cylinder need not be emptied where the devices are used in installations used only during the summer time, and must be disconnected and emptied through the winter to avoid damage from freezing, as in public parks and pleasure resorts only open 105 through the summer.

The retarding piston just described is lifted by means of an arm 39 which is adjustably secured to the pivot 19^a before mentioned and which is rocked when the rod 22 is operated to initiate a flushing operation. The inner end of this arm 39 is arranged to cooperate with the contact member 38 carried by the stem of the retarding piston, and lift it to a height determined by its angular adjustment upon the pin at 19^a. This adjustment is attained by splitting a hub 40 with which the arm 39 is provided, and employing a clamping screw 41 to secure it to the pivot. In this manner the height to 110 115 120 125 130

which the retarding piston is lifted may be varied, and consequently the length of a flush of water may be regulated.

The operation of my novel flushing device will require but brief further explanation. When the actuating rod 22 is operated, the pumping piston 15 is lifted from lowermost to upper position, the water passing freely through and around the piston. Simultaneously, the timing piston is elevated in the cylinder 30, and the lifting of the contact member 38 at the top of the stem 36 releases the lever 28 and permits the valves 25 and 26 (which are held open between flushing operations by such lever through the weight of the contact member and connected parts) to close the openings at the top of the siphonic passage. When the rod is released the weighted main piston 15 will descend upon its return stroke, the check plate 17 being forced against the under side of such piston and closing the openings therethrough, (see Fig. 3^a) and in this manner the starting charge of water in the piston chamber is forced through the chamber 4 and into the descending leg of the siphon to initiate a flush. The check plate then assumes the position shown in Fig. 3^a, and remains in this position during the continuation of the siphonic flow and the ensuing period of rest. The flush having been initiated in the manner described continues until the descent of the timing piston near the end of the return stroke causes the contact member 38 to rock the lever 28 and lift the valve 25. This permits air to enter the central small tube 24, which has the effect of diminishing and retarding, but not entirely interrupting the siphonic flow. The diminished flow continues for a relatively brief period, but long enough to properly refill the closet bowl, and the further descent of the timing piston, by effecting the opening of the valve 26 in a similar manner, causes air to be admitted directly into the bend at the top of the siphonic passage and entirely stops further siphonic action.

I claim:

1. In apparatus for flushing water closets including a master tank and a supply pipe, a siphonic flushing device having an open-topped chamber in free communication above its bottom with said supply pipe, the portion of such chamber below said supply pipe constituting a forcing chamber; a siphonic passage communicating with the bottom of said forcing chamber and having at its top a normally open passage to the atmosphere, a valve governing said passage, a piston in said forcing chamber, and actuating means operatively connected with said valve and piston and arranged to effect closing of the valve and operate said piston.

2. In apparatus for flushing water closets including a master tank and a supply pipe,

a siphonic flushing device having an open-topped chamber in free communication above its bottom with said supply pipe, the portion of such chamber below said supply pipe constituting a forcing chamber, a siphonic passage communicating with the bottom of said forcing chamber and having at its top a passage to the atmosphere, a valve yieldingly tending to close said passage, a piston in said forcing chamber, a reciprocating connection operatively connected with said valve and arranged to permit it to close when such is moved from normal position of rest and connected with said piston and arranged to force water from said forcing chamber through said siphonic passage.

3. In apparatus for flushing water closets including a master tank and a supply pipe, a siphonic flushing device having an open-topped chamber in free communication above its bottom with said supply pipe, the portion of such chamber below said supply pipe constituting a forcing chamber, a siphonic passage communicating with the bottom of said forcing chamber and having at its top a passage to the atmosphere, a valve yieldingly tending to close said passage, a piston in said forcing chamber, a reciprocating connection operatively connected with said valve and arranged to permit it to close at the beginning of a reciprocating movement of such connection and also operatively connected with said piston, said piston being arranged to force water from said forcing chamber through said siphonic passage on its return stroke.

4. In apparatus for flushing water closets including a master tank and a supply pipe, a siphonic flushing device having an open-topped chamber in free communication above its bottom with said supply pipe, the portion of such chamber below said supply pipe constituting a forcing chamber, a siphonic passage communicating with the bottom of said forcing chamber and having at its top a passage to the atmosphere, a valve yieldingly tending to close said passage, timing mechanism including a contact member arranged to hold said valve open when in normal position of rest, a piston in said forcing chamber, and actuating connection operatively connected with said timing mechanism and also operatively connected with said piston.

5. In apparatus for flushing water closets including a master tank and a supply pipe, a siphonic flushing device having an open-topped chamber in free communication above its bottom with said supply pipe, the portion of such chamber below said supply pipe constituting a forcing chamber, a siphonic passage communicating with the bottom of said forcing chamber and having at its top a passage to the atmosphere, a valve yieldingly tending to close said pas-

11 sage, timing mechanism including a cylinder and a retarding piston therein and a contact member connected to said piston and arranged to hold said valve open when said 5 piston is in normal position of rest, a pumping piston in said forcing chamber, and an actuating connection operatively connected with said retarding piston and said pumping piston.

10 6. In a siphonic flushing device having means for forcing a starting charge of water through the siphonic passage, means for governing the length of flow comprising a valve arranged to admit air to the top of 15 the siphon, a cylinder, a reciprocating piston having a retarded return movement operatively connected to said valve and arranged to open it at the end of its return stroke, and means for actuating said piston.

15 7. In a siphonic flushing device having means for forcing a starting charge of water through the siphonic passage, means for governing the length of flow comprising a valve arranged to admit air to the top of 20 the siphon, a cylinder, a reciprocating piston having a retarded return movement and provided with a stem equipped with a contact member, said contact member being arranged to open said valve at the end of 25 the return stroke of the piston, and means for actuating said piston.

25 8. In a siphonic flushing device having means for forcing a starting charge of water through the siphonic passage, means for governing the length of flow comprising a 30 valve arranged to admit air to the top of the siphon, a cylinder, a reciprocating piston having a retarded return movement and provided with a stem equipped with a contact member, a rocking lever operatively connected to said valve, said contact member being arranged to rock said lever and open said 35 valve at the end of the return stroke of the piston, and means for actuating said piston.

40 9. A siphonic flushing device according to claim 8 in which said valve yieldingly tends to close and is normally held open between flushing operations by the weight of said piston mechanism.

45 10. In a siphonic flushing device having means for forcing a starting charge of water through the siphonic passage, means for producing a diminished refill flow comprising a tube extending downwardly into the 50 descending leg of the siphon, a valve for admitting the passage of air through said tube, said valve being closed during the primary flushing flow, and retarded opening means for effecting a delayed opening of 55 said valve.

60 11. In a siphonic flushing device having means for forcing a starting charge of water through the siphonic passage, means for producing a diminished refill flow comprising a tube extending downwardly into the

descending leg of the siphon, a valve for admitting the passage of air through said tube, a reciprocating piston having a retarded return movement operatively connected to said valve and arranged to open 70 it shortly before the end of its return stroke, and means for actuating said piston.

12. In a siphonic flushing device having means for forcing a starting charge of water through the siphonic passage, means for producing a diminished refill flow comprising a tube extending downwardly into the descending leg of the siphon, a valve for admitting the passage of air through said tube, a reciprocating piston having a retarded return movement and provided with 75 a stem equipped with a contact member, said contact member being arranged to open said valve at the end of the return stroke of the piston, and means for actuating said piston.

13. In a siphonic flushing device having means for forcing a starting charge of water through the siphonic passage, means for producing a diminished refill flow comprising a tube extending downwardly into the descending leg of the siphon, a valve for admitting the passage of air through said tube, a reciprocating piston having a retarded return movement and provided with a 80 stem equipped with a contact member, a rocking lever operatively connected to said valve, said contact member being arranged to rock said lever and open said valve at the end of the return stroke of the piston, and means for actuating said piston.

14. In a siphonic flushing device having means for forcing a starting charge of water through the siphonic passage, means for producing a diminished refill flow and then breaking the siphon comprising a tube extending downwardly into the descending leg of the siphon, a valve for admitting the passage of air through said tube, a valve arranged to admit air to the top of the siphon, retarding mechanism operatively connected with said valves and arranged to first open said first-mentioned valve and then open said second-mentioned valve during the latter part of its cycle of movement, and means for actuating said forcing means and said retarding mechanism.

15. In a siphonic flushing device having means for forcing a starting charge of water through the siphonic passage, means for producing a diminished refill flow and then breaking the siphon comprising a tube extending downwardly into the descending leg of the siphon, a valve for admitting the passage of air through said tube, a valve arranged to admit air to the top of the siphon, a reciprocating piston having a retarded return movement and operatively connected to said valves and arranged to first open said first-mentioned valve and then open said second-mentioned valve during the latter part of its cycle of movement, and means for actuating said forcing means and said retarding mechanism.

ond-mentioned valve during the latter part of its return stroke, and means for actuating said forcing means and said piston.

16. In a siphonic flushing device having 5 means for forcing a starting charge of water through the siphonic passage, means for producing a diminished refill flow and then breaking the siphon comprising a tube extending downwardly into the descending leg 10 of the siphon, a valve for admitting the passage of air through said tube, a valve arranged to admit air to the top of the siphon, a reciprocating piston having a retarded return movement and having a lost-motion 15 connection with said first-mentioned valve and a lost-motion connection with said second-mentioned valve whereby they are opened in succession during the latter part 20 of the return stroke of the piston, and means for actuating said forcing means and said piston.

17. In a siphonic flushing device having means for forcing a starting charge of water through the siphonic passage, means for producing a diminished refill flow and then breaking the siphon comprising a tube extending downwardly into the descending leg of the siphon, a valve having a vertical stem and arranged to admit air into said tube, a 25 valve adjacent said first-mentioned valve also having a vertical stem and arranged to admit air to the top of said siphon, a rocking lever operatively connected with the stems of said first-mentioned valve and said 30 second-mentioned valve and arranged to open them in succession, means for actuating said forcing means, and retarding mechanism connected with said actuating means and to said rocking lever and arranged to 35 produce a delayed opening movement of said valves.

18. In a siphonic flushing device having means for forcing a starting charge of water

through the siphonic passage, means for producing a diminished refill flow and then 45 breaking the siphon comprising a tube extending downwardly into the descending leg of the siphon, a valve having a vertical stem and arranged to admit air into said tube, a valve adjacent said first-mentioned valve 50 also having a vertical stem and arranged to admit air to the top of said siphon, a rocking lever operatively connected with the stems of said first-mentioned valve and said second-mentioned valve and arranged to open 55 them in succession, means for actuating said forcing means, a reciprocating piston having a retarded return movement and provided with a stem connected with said actuating means and also having a one-way lost-motion 60 connection with said rocking lever.

19. In a siphonic flushing device having means for forcing a starting charge of water through the siphonic passage, means for regulating the length of flow including 65 a valve arranged to admit air to the top of the siphon, a liquid-filled cylinder, a reciprocating piston in said cylinder operatively connected to said valve and having a retarded return movement, and means for 70 adjustably varying the length of stroke of said piston.

20. In a siphonic flushing device having a pumping piston for forcing a starting charge of water through the siphonic passage and 75 having actuating means including a rock shaft arranged to operate said piston, means for regulating the length of flow including a valve opening into the siphonic passage, a liquid-filled cylinder, a timing piston in said 80 cylinder having a stem operatively connected to said valve, a rock arm connected to said rock shaft and operatively connected with said piston stem, and means for angularly adjusting said rock arm on said rock shaft.

ROBERT A. BROOKS.
